3,356,247 PIVOT MEANS FOR AN ELECTRICAL FITTING OR THE LIKE

Norman Goldsobel, Commack, N.Y., assignor to Electrical Fittings Corporation, East Farmingdale, N.Y., a corporation of New York

Filed Nov. 1, 1965, Ser. No. 505,809
4 Claims. (Cl. 220—31)

This invention relates to pivot means for securing a rotatable cover to a body of an electrical fitting or like structure, whereby the fitting may be easily opened and closed for threading wire therethrough.

The invention illustrated and claimed herein is an improvement of the invention depicted and claimed in my copending application Ser. No. 420,582, filed Dec. 23, 1964, and entitled, Electrical Fitting Entrance Cap.

It is the principal object of this invention to provide an improved pivotal structure for securing a rotatable cover with respect to the body of an electrical fitting or similar structure, whereby the cover is readily assembled to the fitting body and detachable therefrom.

It is a further object of the invention to provide improved pivoting means for electrical fittings such as entrance caps where the fitting may be easily opened and closed for threading wire therethrough by reason of the fact that the cover is securely rotatably captivated to the body for such normal pivotal use of the cover. In addition, the structure of the invention permits the cover to be assembled to the body and disassembled therefrom as well as being opened and closed manually, and this may be carried out by the use of one hand only when the body of the entrance cap is securely attached to a conduit.

Further objects and advantages will become apparent from the following description of the invention taken in conjunction with the figures, in which:

FIG. 1 is a fragmentary view of an electrical fitting in section illustrating the pivotal means in accordance with the invention for rotatably captivating the fitting cover to the fitting body and for attaching and detaching said cover and body;

FIG. 2 is a fragmentary sectional view of the fitting contemplated in FIG. 1 (an entrance cap) and which figure is essentially a right-side view of FIG. 1 wherein the continuous outline of the cover depicts same in closed status and the phantom outline of the cover depicts same in open status;

FIG. 3 is a fragmentary section of the illustrated fitting, which figure is essentially a right-side view of FIG. 1 and depicts the camming action between the pivot key and fitting cover;

FIG. 4 is a perspective view of the pivot key elements in accordance with the invention; and

FIG. 5 is a perspective view of the cover-slot structure for engaging the pivot key, with the cover depicted in upside-down position.

As noted hereinbefore, the pivot means of the instant invention is an improvement of my copending Serial No. 420,582. Reference to such application is made for a detailed description and background explanation of the prior art and the significance of this invention as applied to an electrical fitting such as an entrance cap. Consequently, the structure illustrated and described herein is confined to the specific improvement claimed herein. With the view of simplification, the parts and elements of the pivot structure depicted and claimed herein are individually identified by the same reference numbers used for the corresponding parts and elements of the similar pivot structure of said copending application.

As known in the art, electrical power feeder lines are received by an entrance cap 50 (the fitting con-

2

templated herein) and pass through the interior of entrance cap 50 wherein such wires continue into the wire conduit (not shown herein) to which entrance cap 50 is secured. One advantage of the invention resides in rendering entrance cap cover 51 rotatably secured and latched to an entrance cap body 52 without screw attachment means. As a result, cover 51 is readily attached to body 52 and detached therefrom manually. This may be effected at the place of installation by the electrician, who, standing on a ladder, may carry out the job of threading wire into entrance cap 50 while such fitting is secured to the wire conduit. The structure thus permits the electrician to flip closed cover 51 by his finger or pry open the latched cover 51 by any available 10 prying tool such as the blade of a screwdriver.

Cover 51 is pivotally attached to body 52 by means of an ear 70 extending integrally from cover 51. Ear 70 consists of a pair of flat wall members 71, 72, each essentially at right angle relationship with respect to the other. Member 71 is in a plane substantially parallel to the plane of cover 51, whereas member 72 is in a vertical plane as seen in FIG. 1. Ear members 71, 72 have interconnecting bayonet slots 73, 74. Slot 74 is a lengthwise and narrow width bayonet slot in member 72 communicating with a C-shaped bayonet slot 73 (FIG. 5) of larger width in member 71. Slots 73, 74 operatively engage a key 75 extending axially from an ear 76, which ear 76 is an integral extension of entrance cap body wall 67. Key 75 comprises a small diameter shank 77, an enlarged head 78 at the front of shank 77 and a cam 79a extending upright from the forward face of head 78. The top of cam 79a is rounded at 125 and with head 78 ends in a vertical plane confronting ear 76 to form a gap therebetween, which gap surrounds shank 77. The bottom of cam extension 79a is flat and forms a fulcrum at 80 where it joins with head 78, see FIG. 1. The purpose of fulcrum 80 will be explained hereinafter.

Bayonet slots 73, 74 and key 75 are complementary shaped to permit attachment and removal of cover 51 with respect to body 52, but when these parts are engaged cover 51 is rotationally captivated to body 52 and cannot become accidentally detached therefrom during normal operational use, whether cover 51 is in opened or closed position or while swinging same from one to the other of such positions.

The solid outline in section of cover 51 in FIG. 2 depicts same in closed position. Cover 51 is rotated counterclockwise, as viewed in FIG. 2, to open the entrance cap 50. This is depicted in phantom outline in FIG. 2. Abutment of ear surface 81, see FIG. 5, with body 52 acts as a limit stop. When cover 51 is attached to body 52, bayonet slot 74 is rotatably captivated on shank 77 between ear 76 and the combined structure of enlarged head 78 and its cam extension 79a. Enlarged head 78 is dimensionally wider than slot 74; however as seen in FIG. 2, the width of cam 79a is narrower than the width of slot 74.

FIGS. 1, 2 illustrate the manner of attaching and disassembling cover 51 with respect to body 52. Cover 51 is held upside-down with its ear member 72 in front of key 75 and with bayonet slot 74 substantially upright. Cover 51 is then tilted at about a 45° angle, as depicted in solid outline in FIG. 1, to permit the opening formed by slot 74 and C-shaped bayonet slot 73 to mount over the combined structure of cam extension 79a and enlarged head 78. At this stage of attachment, the edge 82 of slot 73 bears against fulcrum 80 formed by extension 79a and forward surface of head 78. Cover 51 is then pivoted about fulcrum 80 in the direction of arrow 83 (FIG. 1) to align ear member 72 substantially upright in the gap surrounding shank 77. As cover 51 pivots in direction of arrow 83, the opening formed by slots 73, 74 clears passed the head-cam

structure 78, 79a. Cover 51 is then permitted to drop straight down to assume the phantom outline position as shown in FIG. 1. From this moment on, keyway slot 74 is captivated on shank 77 between ear 76 and the confronting vertical face of head 78 and cam 79a. The phantom outline of cover 51 in FIGS. 1 and 2 correspond to an open status of cover 51 with its slot 74 mounted on shank 77. This phantom illustration also depicts the orientation of cover 51 just prior to mounting same on key 75, that is to say, just prior to tilting cover 51 in a 45° angle so as to permit enlarged C-shaped slot 73 to mount over extension 79a and head 78. Cover 51 may now be rotated about the axis of shank 77, see arrow 85 in FIG. 2, to close entrance cap 50 and this is depicted in solid outline in FIG. 2.

Inasmuch as enlarged head 78 is greater than the width of slot 74, once attached, cover 51 whether in its open or closed position and while being rotated from one to the other of such positions remains captivated to body 52. The respective dimension of these coacting parts provide a clearance 86 (see FIG. 1) with respect to body ear 76 to permit tilting and pivoting of cover 51 as it is being mounted on key 75 and removed therefrom. It will also be noted that when cover 51 is in opened status (see FIG. 1), the forward end 126 of extension 79a axially overlaps slot edge 82 to captivate cover 51 in a vertical plane on key 75, should cover 51 for any reason be raised in the direction of arrow 87 shown in FIG. 2.

To remove cover 51, the above-described attachment process is essentially reversed. Cover 51 is opened and then raised in the direction of arrow 87, FIG. 2, for slot edge 82 to engage fulcrum 80. Then cover 51 is rotated clockwise, opposite to the direction of arrow 83, FIG. 1, about 45° until the wide dimension of bayonet slot 73 clears enlarged head 78 while slot 74 passes over cam extension 79a to permit removal of cover 51.

Cover 51 is snap-latched to body 52 by a detent finger 89 punched from a tab 90 depending integrally from cover 51. Body wall 67 includes an outstanding boss 91, whereby upon closing cover 51, the upper edge of finger 89 spring-snaps under boss 91. A guide stud 92 at the rear of boss 91 extends outwardly from body wall 67. The rear edge of tab 90 is designed to bear against stud 92. This bearing engagement maintains cover 51 properly aligned with respect to body 52 for latching and unlatching cover 51. Cover 51 is easily unlatched to open same by prying a screwdriver blade or like object under tab 90 to lift same up, whereby finger 89 clears boss 91.

The high-dome cam 79a serves to maintain proper operating alignment of cover 51 with respect to body 52. When cover 51 is in open status, depicted in phantom outline in FIG. 1, the back wall of high-dome cam 79a acts as a limit stop against which the adjacent surface of cover ear 72 abuts. This limits the clockwise tilt of cover 51 due to its weight. That is to say, by holding ear 72 in a more pronounced vertical plane within the gap surrounding shank 77, a better operating cover alignment is achieved upon swinging cover 51 closed. It is recalled that cover 51 is attached to body 52 by reason of cover slot 74 being captivated on body shank 77. Hence, as cover 51 continues to swing clockwise to close, as viewed in FIG. 3, cover ear 72 tends to ride along shank 77 in a direction to misalign cover 51 with respect to body 52. Such misalignment could result in tab 90 not aligning properly with respect to guide 92 and boss 91. The high dome and rounded surface 125 acts as a cam upon which the underside of cover ear 71 rides as cover 51 approaches its closed position, see FIG. 3, except now cover 51 is turning opposite to arrow 49. Camming cover 51 in this manner maintains same properly aligned with respect to body 52. As a result, when the electrician flips cover 51 to close, tab 90 automatically drops into proper contiguous relationship against guide 92, thus automatically aligning

finger 89 to snap under boss 91. Such spring-snap is effected by the electrician pressing down with his hand on cover 51.

Another advantage achieved by the high-dome cam 79a is also depicted in FIG. 3. A hard pivot force is applied in the direction of arrow 49 (FIGS. 2 and 3) to pry open a latched cover. As cover 51 swings counterclockwise through intermediate positions receding from its closed status, cover ear 72 tends to ride along shank 77 in a direction to close the gap G between the end 172 of ear 72 and the adjacent body wall 67. If cover ear 72 rides too far down on shank 77, its end 172 will wedge against the adjacent body wall 67 and this is not desirable. The high dome and rounded surface 125 prevents such contact occurring. During an opening swing, should the impact of the prying force urge key 75 to ride relatively up slot 74, the undersurface of cover ear 71 cams against the rounded surface 125, as depicted in FIG. 3, thereby preventing ear 72 ever coming into contact with body wall 67.

It is intended that all matter contained in the above description or shown in the accompanying drawing shall be interpreted as illustrative and not in a limiting sense.

What is claimed is:

1. Pivot means for an electrical fitting or the like comprising, a fitting body, a cover pivotally connected to said body for opening and closing said electrical fitting, said cover and said body having first and second mutually engageable means coacting for rotatably captivating said cover and said body, said first means including a plurality of spacially related communicating slots, said second means including a wall having a multisected key extending axially from said wall, said key having tandem sections complementary in shape to respective sections of said related slots, whereby said cover being attachable to and detachable from said body upon said cover assuming a given positional status relative to said body, but otherwise said cover being rotatably captivated to said body for operatively opening and closing said cover, said key including a shank section intermediate said back wall and a relatively enlarged section at the forward end of said shank section, said enlarged section including a camming extension coacting with said cover for maintaining suitable operative alignment of said cover with respect to said body as said cover is pivotally flipped closed and as said cover is opened.

2. Pivot means as defined in claim 1 further including, means on said cover and body for latching said cover in closed status to said body, said cover having an outwardly extending ear and said ear including said plurality of slots, said key wall being an integral part of said body, said ear being captivated on said key shank between said wall and enlarged section for maintaining alignment of said cover and said body for latching of said cover to said body upon flipping said cover closed.

3. Pivot means as defined in claim 1, said cover having an outwardly extending ear, said ear including said plurality of slots, said key wall being an integral part of said body, said ear being captivated on said key shank between said wall and enlarged section, said camming extension being juxtaposed said ear when said cover is in closed status for camming said cover to prevent wedging of said cover ear against said body as said cover is pivotally flipped to open status.

4. Pivot means as defined in claim 3 further including, means on said cover and said body for latching said cover in closed status to said body, said camming extension also being juxtaposed said ear as said cover is pivoting to a closed status for maintaining alignment of said cover for latching same to said body.
